FRANK LANE, OF CARTHAGE, AND OLIVER E. OAKES, OF JOPLIN, MISSOURI.

STEAM-ENGINE.

SPECIFICATION forming part of Letters Patent No. 756,657, dated April 5, 1904.

Application filed April 11, 1902. Serial No. 102,397. (No model.)

To all whom it may concern:

Be it known that we, FRANK LANE, of Carthage, and OLIVER E. OAKES, of Joplin, in the county of Jasper and State of Missouri, have invented a new and useful Improvement in Steam-Engines, of which the following is a specification.

The object of our invention is to provide a steam-engine which shall occupy the least possible space, shall be free from danger of boiler explosions, which shall use steam at very high temperature and pressure with least possible loss by condensation and radiation, and which shall give the greatest amount of power for the fuel consumed and which shall also involve only a small current expense for running the same.

To these ends our invention consists of an engine of that principle of action known as "flashers," or steam-engines which have no boiler proper and carry no permanent body of steam, but inject upon heated surfaces small quantities of water at each movement of the piston, which limited quantity of water is instantly expanded or flashed into steam to give a single impulse to the piston and which injections of water and steam impulses are repeated at every movement of the piston. We have invented a new and useful engine of this type, which we will now proceed to describe with reference to the drawings, in which—

Figure 1 is a side elevation of the entire engine. Fig. 2 is a side elevation looking at right angles to the view shown in Fig. 1 and with one-half of the engine shown in section, and Figs. 3, 4, and 5 are enlarged details.

In the drawings, A represents the cylinder of the engine, which is arranged vertically and is open at the top. At its bottom it is supported upon a base B, which is of circular form and has short upwardly-extending legs a², supporting a circular ring a³ at the top, between which and the bottom of the cylinder a stout plate a, of copper, is secured by bolts a⁴, as seen in Fig. 1. This plate a closes the bottom of the steam-cylinder, and between this plate a and the bottom of the base B there is formed an open space or retort-chamber for burners or heating-jets of flame, by

which the plate a is raised to a high temperature. The plate a we term a "flash-plate," as the spray of water injected upon it is flashed into steam. The internal bore of the cylinder A is somewhat smaller at its lower end than it is at the upper end, and within said cylinder is fitted to slide vertically a cup-shaped piston R, which has at its upper edge an outturned lip fitting the larger upper diameter of the cylinder. A rocking bearing b of this piston is connected by a piston-rod b² with the crank F of the main shaft F' F², which latter is journaled in boxes e e' in the tops of standards E E', mounted upon the opposite sides of the top of the cylinder, and is provided at its opposite ends with band-wheel G and balance-wheel G'.

On one side at its lower edge, the cylinder A has a projecting table-surface A', resting upon the base B, and on this table is erected a single-acting pump C, which consists of a short cylinder bolted to the top of the table A' and made to cover two channel-ways c c'. One of these channels, c', takes water from any source of supply, and c' communicates with a passage-way c², which is formed in the ring a³ and opens through a check-valve c⁴ into the interior space of the cylinder A above the copper plate a. Fig. 3 is a detail view in section of this check-valve in the cylinder of the engine. A is the wall of the cylinder. A⁵ is a plug screwed in the part A', which plug is to be removed to examine or repair valve-frame c⁵ or valve c⁴. The valve-frame c⁵ is screwed in the plate a and consists of a regulation seat with an arm extending over the valve and acting as a guide for the stem and spring c⁶. When the plunger c of the pump C rises, it draws in water through the passage-way c', and when said plunger descends it forces a definite and regulatable amount of water out through the passage-ways c² c³ and valve c⁴ onto the top of the highly-heated plate a, where it becomes instantly converted into steam and whose pressure being exerted on the piston R lifts the same. The water-piston c of the pump is lifted by the action of an eccentric K on the main shaft F' above, but has a quick and variable descent, accord-

ing to the amount of water to be injected at each stroke. The power for the descent of the pump-piston is supplied either by a coil-spring s , as shown, or by a dash-pot. To limit the 5 downward drop of the pump-piston, an adjustable stop d^2 is fixed to the piston-rod, and just beneath it (see Fig. 1) an inclined slide d^3 is made to be adjusted on an-inclined track d^4 , formed on or attached to the side of the cylinder. By sliding the piece d^3 up or down on the track d^4 the upper surface of the slide d^3 is made to arrest the fall of the stop-piece d^2 sooner or later in its descent. For lifting the 10 pump-piston (see Figs. 1, 4, and 5) the eccentric K has a rod d^7 , that is jointed to a slide d^8 , carrying a pivoted grab-hook d^9 , which acts upon a lug d^0 , attached to the piston-rod c^5 , and after lifting it a sufficient distance releases it and allows it to rapidly fall in response to the 15 spring s or a dash-pot. The slide d^8 has a dovetail rib d^{10} , that slides in a corresponding groove d^7 in a block M , attached to the cylinder. The piston-rod c^5 is guided at its upper end by a dovetail slide c^6 , working in a groove 20 in the block M . The grab-hook d^9 is thrown under the lug d^0 by the spring d^{11} , and after lifting the piston-rod by said lug the grab-hook is thrown off the said lug by a leg d^{12} of the grab-hook, which comes in contact with a 25 stationary cam d^{13} on the block M , the said leg d^{12} being made rigid with the grab-hook, so that the action of cam d^{13} on the rigid leg d^{12} is transmitted to the grab-hook to dislodge it from the leg. The grab-hook is of sufficient 30 length to allow a full stroke of the eccentric to be made and to allow the pump-rod to be stopped at any point of its upstroke by the cam d^{13} in regulating the amount of water to be admitted to the cylinder, for which purpose the cam d^{13} may be made vertically adjustable in any suitable manner.

On the opposite side of the cylinder from the pump there is formed an exhaust-chamber A^2 for the steam. This communicates with 45 the interior of the cylinder near its bottom and has a discharge-pipe A^4 leading to the outer air. In a circular seat within this chamber A^2 there is arranged a rocking valve A^3 , which at one end has a crank-arm e^4 , connected by a rod e^1 with a horizontal bar e^3 , which in turn is fulcrumed near its middle to a support e^0 from the cylinder and is at its other end connected to the eccentric-rod e^2 , which is worked by the eccentric K' on the main shaft. 50 The rod e^1 has at top and bottom ball-joints for connecting with lever e^5 and valve-arm e^6 . The rotary valve A^3 has an opening in its side extending a little more than a semidiometer, and through it the steam escapes from the 55 lower portion of the cylinder to the discharge-pipe A^4 . This discharge of steam takes place immediately after the piston has reached the highest portion of its stroke, and the discharge-valve remains open during the greater 60 part of the descent of the piston. At other

times or during the expansion of the water into steam and the rise of the piston the solid part of the rocking valve is turned by the action of the eccentric so as to cut off the discharge of steam.

For regulating the position of slide d^3 , and consequently the stroke of the pump and quantity of water injected at each stroke, this may be done by hand or in any other way—as, for instance, by any automatic speed-governor 75 which we contemplate applying to our engine.

The object in using a copper plate a at the bottom of the engine to receive the spray of water is to prevent oxidation of the metal, and for this purpose various alloys or non- 80 oxidizing metals may be used.

At the bottom of the cylinder it will be perceived that the steam-space is widened out adjacent to the flash-plate a beyond the diameter of the piston. Into this widened-out 85 space the water is injected and spread over the plate in a spray, and from this space also the steam is gathered for the discharge.

Having thus described our invention, what we claim as new, and desire to secure by Letters 90 Patent, is—

1. A flasher-engine having a water-injection pump, means for positively withdrawing the plunger of the pump, means for disconnecting the said plunger, and resilient means 95 for quickly advancing the plunger of the pump to inject the water substantially as described.

2. A flasher-engine having a vertical cylinder, a plunger working therein and a flash-plate at the bottom said cylinder being enlarged laterally at its lower end adjacent to the flash-plate to a greater diameter than the plunger, and having its water and steam-valves opening into said enlargement substantially as and for the purpose described.

3. In a steam-engine of the kind described the combination with the cylinder, its piston, and a highly-heated flash-surface; of a water-injection pump, a spring or its described equivalent for forcing down its plunger, and an eccentric on the main shaft with means for lifting the pump-plunger and releasing it with a quick drop substantially as and for the purpose described.

4. In a steam-engine of the kind described, the combination with the cylinder, its piston, and a highly-heated flash-surface; of a water-injection pump, a spring or its described equivalent for forcing down its plunger, an eccentric on the main shaft with means for lifting the pump-plunger and releasing it with a quick drop, and an adjustable stop for limiting the throw of said pump-plunger and consequently the amount of water injected substantially as described.

5. In a steam-engine of the kind described, the combination of the cylinder A having table extension A' with passage-ways c^1 c^3 , the pump mounted above the same, and the base 130

having ring a^3 with passage-way c^3 , the flash-plate interposed between the said ring and cylinder, and the valve c^4 substantially as and for the purpose described.

5 6. In a steam-engine of the kind described, the cylinder having a discharge-chamber A^2 formed at its lower end and communicating with the interior, the rocking valve A^4 arranged in the same and having crank e^4 , an eccentric on the main shaft, a horizontal lever e^3 ,

rod e' connecting one end of the said lever to the crank of the discharge-valve, and rod e^2 connecting the other end of the lever to the eccentric.
